DESIGN FOR A DEFLECTOR FOR INFANTS' TOILET SEATS

Maurice Sacheroff, East Cleveland, Ohio

Application August 28, 1936, Serial No. 64,618

Term of patent 14 years

To all whom it may concern:

Be it known that I, Maurice Sacheroff, a citizen of the United States, residing at East Cleveland, in the county of Cuyahoga, and State of Ohio, have invented a new, original, and ornamental Design for a Deflector for Infants' Toilet Seats, of which the following is a specification, reference being had to the accompanying drawing, forming part thereof.

Figure 1 is a front perspective view of a deflector for infants' toilet seats, showing my new design and Figure 2 is a rear perspective view thereof.

I claim:

The ornamental design for a deflector for infants' toilet seats, as shown.

MAURICE SACHEROFF.
